UNITED STATES PATENT OFFICE.

ANDREW J. MARKHAM, OF DANA, IOWA, ASSIGNOR OF ONE-TENTH TO CHARLES A. SWANSON, ONE-TENTH TO CHARLES A. SENTER, ONE-TENTH TO EDGAR J. CLARK, ONE-TENTH TO GEORGE W. MORRIS, AND ONE-TENTH TO WILLIAM C. JOHNSTON, ALL OF DANA, IOWA.

CORN-HUSKER.

1,133,736.

Specification of Letters Patent.

Patented Mar. 30, 1915.

Original application filed March 3, 1913, Serial No. 751,898. Divided and this application filed July 29, 1913. Serial No. 781,845.

To all whom it may concern:

Be it known that I, ANDREW J. MARKHAM, a citizen of the United States, residing at Dana, in the county of Greene and State 5 of Iowa, have invented a new and useful Corn-Husker, of which the following is a specification.

This invention relates to corn husking machines and is more particularly a division of 10 an application filed by me on March 3, 1913, Serial No. 751,898.

One of the objects of the invention is to provide improved means whereby the ears of corn may be husked, the ears, as well as 15 all loose grains of corn, being directed to an elevator which will convey them to a wagon or other receptacle disposed adjacent the machine.

A further object is to provide improved 20 means whereby the husks are packed between the rolls of the husking mechanism.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 30 within the scope of what is claimed, without departing from the spirit of the invention.

In the accompanying drawings the preferred form of the invention has been shown.

35 In said drawings:—Figure 1 is a plan view of the machine. Fig. 2 is a longitudinal section on line A—B Fig. 1.

Referring to the figures by characters of reference 1 designates the revolute axle 40 supported by wheels 2 which are adapted to rotate therewith. A frame 3 is supported by the axle and connected to the rear portion of the frame 3 is a rear frame 4. The rear end portion of the rear frame 4 has a 45 steering mechanism 6. Arranged transversely upon the rear frame 4 close to the back end of the frame 3 is a trough 21 having an outlet adjacent one end of the machine, the bottom of the trough being inclined downwardly toward said outlet. An 50 inclined elevator casing 22 extends upwardly and laterally from the machine at the discharge end of the trough 21 and in

this casing is arranged an endless elevator belt 23 preferably provided with cross cleats 55 24. The lower portion of the conveyer belt is mounted on a shaft 25 which extends forwardly and is provided at its front end with a gear 26 constantly meshing with a gear 27 secured to the axle 1. This gear is also provided with peripheral sprocket teeth 28 engaging a drive chain 29, this chain receiving motion from a sprocket 30 secured to a transverse shaft 31. This shaft 31 is journaled on the upper end portions of inclined 65 beams 32 which are fixedly connected to the front end of the frame 3 and are extended downwardly and forwardly therefrom. A sprocket 33 is secured to shaft 31 and receives motion, through a chain 34, from a 70 motor 35 mounted on one side of the frame 3 adjacent the back thereof. A water tank 36 is mounted on said frame adjacent the other side so as to counterbalance the motor.

A longitudinal shaft 48 is journaled at 75 each side of the machine and provided with a bevel gear 49 which meshes with another bevel gear 50 secured to a shaft 81. A fly wheel 51 may be secured to each of the shafts 48. Between the shafts 48 is arranged an upwardly extending platform 65 from the sides of which extend upstanding walls 66. A transverse shaft 68 is journaled in the upper end portions of the walls 66 and carries a roller 69 engaged by an endless conveyer 85 apron 70. This apron is inclined downwardly and forwardly along the upper surface of the platform 65 and may be provided with transverse cleats 73 for engaging the corn and carrying it upwardly. Shaft 90 68 receives its motion through a gear 74 meshing with another gear 75 secured to the shaft 31.

Supported by the frame 3 back of the beams 32 are downwardly and rearwardly inclined side walls 80 in which is journaled a shaft 81 having a sprocket 82 which receives motion, through a chain 83, from another sprocket 84 secured to the shaft 31. This shaft 31 has sprockets 85 engaged by 100 endless chains 86 connected by slats 86' to form a conveyer. This conveyer is inclined downwardly and rearwardly and is mounted upon sprockets 87 arranged between the lower end portions of the side walls 80. An 105 inclined riffle 87' is located under the top

of the conveyer and an inclined board 88' is located under the conveyer for directing loose corn into the trough 21. Transverse beams 88 connect the side walls 80 near the upper and lower ends thereof and journaled in these beams are shafts 89 carrying husking rolls 90. The upper end portions of the shafts 89 have gears 91 which mesh with each other, it being understood that the shafts 89 are arranged in pairs and that the gears of each pair mesh so that the shafts of each pair will rotate in opposite directions. One shaft of each pair has a bevel gear 92 at its upper end, this gear meshing with another gear 93 secured to the shaft 31. Shafts 94 extend across the space between the side walls 80 and have cranks 95 which are journaled in the side walls 80. An arm 96 extends downwardly from one of these cranks 95 and is connected, by a pitman 97, to a crank arm 98 arranged at one end of the shaft 31. The shafts 94 are secured to the end portions of a block 99 carrying brush bristles 100, this block and its bristles being adapted to work up and down within the space between the walls 80 when the crank arms are swung back and forth by the pitman 97 and the crank arm 98.

It will be apparent that when the motor is in operation and driving the mechanism of the machine, the said machine will be propelled forward, motion being transmitted to the axle 1 and the wheels 2 by chain 29, this chain receiving motion from sprocket 30 secured to shaft 31 which, as hereinbefore explained, is driven by the motor through chain 34. At the same time motion is transmitted through chain 83 to shaft 81 and the gears 50 thus drive gears 49 and cause the shafts 48 to rotate.

The apron 70 is operated continuously through gears 75 and 74 and shaft 68 and ears, when deposited on the apron will be carried upwardly and drop onto an apron 101 along which they will gravitate onto the upper ends of the husking rolls 90. These rolls, as hereinbefore stated, are arranged in pairs, the rolls of each pair rotating in opposite directions and said rolls receiving motion through the gears 93, 92 and 91. As the ears pass downwardly along the inclined husking rolls 90, the block 99 and bristles 100 are moved downwardly and upwardly so as to press the ears against the husking rolls thus forcing the husks posi-

tively into engagement with the rolls and dragging the ears longitudinally along the rolls with an intermittent motion. Thus the husking of the ears is insured and the husks will drop onto the rifle 87' which is located under the rolls 90 and will be conveyed by chains 86 and slats 86' upwardly to the upper end of a discharge chute 102 arranged under the apron 70. The ears, after being acted on by the husking rolls, will drop into the trough 21 and slide along the inclined bottom thereof to the lower end of the elevator casing 22 where they will be engaged on the cleats on the apron 23 and raised to the upper end of the casing 20 from which point they will be discharged into a wagon or other receptacle at the side of the machine.

By referring to Fig. 2 it will be seen that the bottom of the brush diverges upwardly from the husking rolls at certain times during the actuation of the brush so that a contracted throat is thus produced into which the ears are discharged, thus insuring contact between the brush and the ears.

What is claimed is:—

A corn husker including pivotally connected frame structures, means for supporting the outer ends of each of said structures, husking rolls supported by and movable with one of the frame structures, means for shifting said structures angularly relative to each other, thereby to vary the incline of the husking rolls, means carried by the other frame structures for receiving material discharged from the ends of the husking rolls, and means above and adjustable with the husking rolls for packing ears upon and feeding them along the rolls, said means including a crank shaft extending transversely above the rolls, a brush interposed between and connected to the crank shaft and having its lower active face normally inclined outwardly away from the rolls thereby to form an ear receiving throat, and means for rotating the crank shaft, thereby to move the brush downwardly and outwardly relative to the husking roll.

In testimony that I claim the foregoing as my own, I have hereto affixed my signature in the presence of two witnesses.

ANDREW J. MARKHAM.
